UNITED STATES PATENT OFFICE.

JOHN MILTON EBERSOLE, OF ALLIANCE, OHIO, ASSIGNOR OF TWO-THIRDS
TO A. S. MEARS, OF NEW BRIGHTON, PENNSYLVANIA.

LAND-ROLLER.

SPECIFICATION forming part of Letters Patent No. 735,479, dated August 4, 1903.

Application filed April 20, 1903. Serial No. 153,463. (No model.)

To all whom it may concern:

Be it known that I, JOHN MILTON EBERSOLE, a citizen of the United States of America, residing at Alliance, in the county of Stark and State of Ohio, have invented certain new and useful Improvements in Land - Rollers, of which the following is a specification, reference being had therein to the accompanying drawings.

This invention relates to certain new and useful improvements in land-rollers, and relates specifically to the manner in which the rollers are mounted in their frame, the object of the invention being to provide means whereby one end of the rollers will elevate freely of the other end when engaged with an obstruction, such as a stone or the like.

Briefly described, the invention comprises a supporting-frame provided with a central bracket common to the inner end of both rollers, and which bracket has a slot-bearing to receive the inner ends of the axle or bearing-shaft of the rollers. Suitable bearings are provided for the outer ends of the rollers, whereby the inner ends of the same are permitted to elevate independently of the outer ends.

In describing the invention in detail reference is had to the accompanying drawings, forming a part of this specification, and wherein like numerals of reference indicate like parts throughout the several views, in which—

Figure 1 is a detail perspective view of my improved roller, illustrating how the inner end of one roller may elevate independently of the outer end of the same roller and independently of the other roller. Fig. 2 is a detail perspective view of the supporting-frame with the rollers removed. Fig. 3 is a fragmentary top plan of the rollers, the central bracket being shown in section. Fig. 4 is a detail perspective view of one of the bearings for the outer ends of the rollers.

To put my invention into practice, I provide a substantially rectangular frame 1, to which the draft tongue or bolt 2 is suitably connected, and to the ends of this rectangular frame are attached bearing-brackets 3, carrying the upper member 4 of the end bearing. This end bearing comprises an upper member 4 and the lower member 5, said upper member

carrying screws 6, which pass through openings provided therefor in the lower member 5, and the latter is secured in position by means of nuts 7. The lower member 5 and the upper member 4 are provided with sockets 8 to receive the ball 9, formed on the end of the shaft 10 of the rollers 11, the neck 12 of said shaft operating in the opening or groove 14, provided therefor in the end bearing. The groove and seat 14 of this end bearing are made at an incline to permit the elevation of the inner end of the rollers. The inner end of the shaft 10 is reduced in size, and its end 15 engages in the slot 16, provided therefor in the central bearing-bracket 17, carried by the frame and suitably secured thereto, the present illustration showing the bracket 17 affixed to the lugs 18, depending from the side bars of the frame. In case one of the rollers meets an obstruction, such as a stone or the like, it will be observed that the roller is free to incline or elevate at its one end without elevating the roller throughout its entire length, thus allowing the portion of the roller to remain in engagement with the surface being rolled. The device is adapted particularly for land-rolling, though it is by no means limited to this purpose, as it will be employed in any connection where rolling is desired.

In the practice of the invention it will be noted that various changes may be made in the details of construction without departing from the general spirit of the invention.

Having fully described my invention, what I claim as new, and desire to secure by Letters Patent, is—

In combination with the frame provided at an intermediate point with depending lugs, bearing-brackets secured to the opposite ends of the said frame, bearings secured to said brackets, a bracket secured to said lugs and being provided with a slot, rollers arranged on opposite sides of said last-named bracket and having their axes arranged in the respective bearings and the slot of the said intermediate bracket.

In testimony whereof I affix my signature in the presence of two witnesses.

JOHN MILTON EBERSOLE.
